UNITED STATES PATENT OFFICE.

FRANK S. THAYER, OF SPOKANE, WASHINGTON, ASSIGNOR OF ONE-FOURTH TO GEORGE C. RICE, OF SPOKANE, WASHINGTON.

ELECTRICALLY-CONTROLLED TRAIN-OPERATING MECHANISM.

1,259,928.

Specification of Letters Patent.

Patented Mar. 19, 1918.

Application filed July 25, 1916. Serial No. 111,191.

To all whom it may concern:

Be it known that I, FRANK S. THAYER, a citizen of the United States, residing at Spokane, in the county of Spokane and State of Washington, have invented certain new and useful Improvements in Electrically-Controlled Train-Operating Mechanisms, of which the following is a specification.

10 My invention relates to improvements in electrically controlled train operating mechanisms, and more particularly to a block signaling system and an apparatus or mechanism carried by the locomotive, designed to 15 coöperate therewith to effect the automatic application of the train brakes.

In a general way, the object of my invention is the provision of an organization of the foregoing character which will be 20 positive in its action, thoroughly practical and reliable under all the conditions and circumstances incident to the operation of railroad trains of whatever type, whether freight or passenger, and especially to provide a system and apparatus which embodies all the elements and qualities to insure safety deemed essential and requisite, as set forth in the reports of the Government and railroad commissions assigned to investigate the subject.

Broadly, my invention comprises, in combination with a permanently closed electrical block signal circuit employing the rails and suitable wire connections and conductors and the customary visual fixed signals along the trackway arranged to indicate "danger" upon the shorting of said circuit as, for instance, when a train is occupying an adjoining block, or a break or ground 40 occurs in the line, but which will normally indicate a "clear" track, of a device, preferably consisting of a third-rail section mounted along the track and electrically connected with the said closed circuit; and 45 an electrically controlled brake setting mechanism carried by the engine designed to coöperate with said third-rail section to actuate the brakes of the train.

Further than this my invention resides 50 in the novel features of construction, combination and arrangement of elements and parts as will be hereinafter particularly described and claimed.

In the accompanying drawings forming a part of this application:—

55 Figure 1 is a diagrammatic plan view of a track section showing a complete block and the contiguous portions of the adjoining blocks, wired to meet the requirements of my invention, the arrangement shown being designed for a single track system to accommodate trains passing in either direction.

Fig. 2 is a similar view showing my arrangement of wiring for a double-track system.

60 Fig. 3 is a diagrammatic plan view showing the several electrical circuits which I employ and which are installed upon an engine together with my third-rail contact device.

Fig. 4 is an enlarged detail view of the device designated by the numeral 70 in Fig. 3.

Fig. 5 is a "head-on" view of a locomotive 75 showing the third-rail contact devices mounted thereon on either side and forward of the front wheels thereof.

Fig. 6 shows a section of an engine cab with the steam and air valves and my automatic actuating gearing in side elevation mounted therein.

Fig. 7 is a side view in elevation of the forward end of a locomotive showing my third-rail contact device mounted thereon and in 85 operative relation with the third-rail section.

Fig. 8 is an enlarged detail plan view of one unit of my electrical equipment which is mounted in the engine cab.

90 Figs. 9 and 10 are enlarged detail views of the parts shown in Fig. 8 and indicated by the numerals 49 and 66 respectively.

Referring specifically to the drawings in which like reference characters indicate like parts in the several views, and first describing that portion of my train controlling apparatus comprising the block wiring and third-rail contact member as disclosed in Fig. 2, which figure shows a complete block designated by the letter Y, and adjoining blocks X and Z, the main circuit consists (see block Y) of a battery 1 located at one end of the block and connected through the medium of the wires 2, 3, 4, 5 and 6, and rails 7 to the magnetic-relay 8 located at the op-

posite end of the block, completing a closed circuit. Wires 9 and 10 lead from said relay to the ends of the track-section 11 of the adjoining block and to the third-rail section 12 mounted parallel therewith, said third-rail section being of a height slightly above the rails of the track. Interposed in the line connecting said relay and sections is the signal box 13.

10 In Fig. 1, which is a single track system of wiring embodying the same principles of operation but arranged to accommodate trains passing in both directions on a single track, in addition to the foregoing described 15 main closed circuit, each third-rail section 12 and track-section 11 is connected by means of the wires 14 with like sections upon the opposite sides of the track in the blocks next adjoining the succeeding and 20 preceding blocks.

The utility of the foregoing closed circuit, relay, and track and third-rail sections will be later explained after I have described those elements of my apparatus which are 25 mounted upon the locomotive and which are designed to coöperate therewith.

In Fig. 3 I have shown a diagrammatic plan view to include the several electrical circuits and third-rail contact members or 30 shoes carried by the engine and which serve under certain conditions to automatically set the air-brakes of the train and shut off the steam.

The main engine circuit comprises the battery 15, or other source of power, wires 16, 35 21, 22, and 25, electromagnetic-switch 17, the pulleys 18 and 20, steel or metal belting 19, switch 23, and shoes or third-rail contact members 24, a normally closed circuit which 40 energizes the said switch 17.

An additional, normally "open" secondary circuit, is composed of the battery 25, wires 26, 27, 28, and 29, signal armature 30, connecting post or brush 31, sleeve 66, and 45 motor 32, the break in the circuit occurring between the said signal armature and the wire 27.

A spring 33 is attached to the signal armature as shown and serves to operate the 50 pivoted signal-armature 30 to complete or close the said secondary circuit upon the de-energizing of the electromagnetic switch 17, which would result from a break in its circuit, for instance, at the switch 23.

55 The function of the motor in the secondary circuit, when the circuit is closed in the foregoing manner, is to operate a brake-valve and steam control valve in the cab to shut off the steam and apply the air-brakes.

60 In Fig. 6 is shown the automatic steam-valve operating and brake-setting mechanism, distinct from the engineer's customary 65 manual controls, which is actuated by the motor 32, and consists of a crank 34 on the shaft 35 of the motor, the crank having a

pin 36 which operates in the slot 37 in the bar 38 connected with the lever-arm 39 on the steam control shaft 40. A gear-wheel 41, also mounted on the shaft of the motor, meshes with the gear-wheel 42 which latter 70 has a pin 43 which operates in the slot 44 of the bar 45 which is connected at its upper end with the lever-arm 46 on the air control shaft 47.

From the foregoing description of the 75 block circuit and the engine apparatus, it is evident that when an engine equipped with the contact shoe, which latter is normally in the position shown in Fig. 3 by reason of its weight and the action of the 8 spring 24^a, and the switch 23 being normally closed as shown, travels upon the rail-section 11 and the said shoe 24 comes in contact with the raised third-rail section 12, the switch 23 will be thrown open as 85 shown in Fig. 7.

Then, assuming that this occurs in, say the block Z (Fig. 2), and that a train is occupying block Y, under which latter condition the closed circuit of the block Y will 90 be shorted through the wheels and axle of the locomotive and the magnetic-relay 8 demagnetized, it is obvious that a break will occur in the circuit composed of the said main engine circuit from the shoe 24, the 95 wheel of the engine in contact with the rail-section 11, through wires 9 and 10 leading from said rail-section and third-rail section, at the magnetic-relay 8, thus effecting the demagnetization of the magnetic-switch 100 17 in the engine cab, and allowing the signal armature 30 having the signal 33^a, to contact with the wire 27, thus serving to complete the secondary circuit and bring into 105 operation the said motor 32 which latter as aforesaid, will operate the steam and air valve mechanism described to shut off the steam and apply the brakes.

On the other hand, should there be no 110 train in the block Y, nor any break in the said closed block circuit due to a break or ground, it is apparent that the said magnetic-relay 8 under such condition being closed, a complete circuit will still exist, and the magnetic-switch in the engine cab re- 115 main closed and the said main engine circuit complete so that the motor 32 will not be energized to effect the application of the brakes and throttling of the engine.

In Fig. 8 is shown the details of the cab 120 signaling device, wiring, and magnetic-switch previously referred to, which controls the air and steam valves. This mechanism is preferably housed as shown and is designated by the numeral 48 in the view, 125 Fig. 6. The signal-armature 30, which is snapped over upon the demagnetization of the magnetic-switch 17, is retained in position, so that the signal 33^a mounted thereon will indicate "danger," by the spring-catch 130

49, a detail view of which is shown in Fig. 9. The wire connected thereto leads to the motor 32 which operates the steam and brake valves through the circuit and in the manner already described. After a train has passed a third-rail section preceding an occupied block, the engineer may, by pressing the said button 50 release the said signal-armature so as to prevent further application 5 of the brakes as the said magnetic-switch 17 will be reenergized as soon as the engine has passed said third-rail section, by reason of the contact shoe member dropping to its normal position to close the switch 23 on the engine, so that such release 10 of the signal-armature will complete the main engine circuit, break the circuit which operates the brakes by deenergizing the brake-setting motor 32 and allow the train to proceed. But, if the engineer does not press the said button, the brake-control 15 will continue to "emergency-air" and stop the train.

In Fig. 6 is disclosed a separate motor 51 connected by wires 52 with the battery 25. This motor, through the medium of the gearing 53 and the governor 54, serves, while the same is in motion, to maintain the air release valve 55 in the air-pipe closed. But if battery 25 becomes exhausted, thus allowing the motor to stop, the said valve will be opened and the air released to effect the setting of the brakes.

An additional feature of my invention is disclosed in Figs. 3, 4, and 10, comprising a means whereby, when the speed of the train reaches a predetermined excessive rate, an electric circuit is completed to operate the air and steam valve actuating motor 32, irrespective 35 of the third-rail device. This device (see Fig. 3) includes the motor 32, battery 25, wires 26, 28, 29 and 56, governor shaft 64, bearing member 64^a, plug 58 adapted to be inserted in one of the holes 59 in the indicator-arc 60, and the pivoted indicator-arm 61 having one end forked as at 62 to receive the disk 63 which is movable longitudinally on the governor-shaft 64 and operated by the governor 65. It is apparent 40 that when the arm 61 contacts with the plug 58, placed at a predetermined point in one of the holes in the arc 60, it will serve to close the circuit just described and to thereby operate the said motor 32 to shut off the steam and make application of the air-brakes. It is also apparent that the said circuit will be again broken when the speed of the train has been sufficiently reduced or retarded so that the arm 61 no longer contacts 45 with the plug.

Still another feature of my organization comprises a means whereby the train may be allowed to pass a "stopping" third-rail section without there ensuing any application 50 of the brakes, provided that the rate of speed

is sufficiently reduced—say to ten miles per hour. To accomplish this result I employ the sleeve 66 which has an insulated portion or section 67, and which is secured on the slidable collar 68 of the governor 65, clearly 70 shown in Figs. 8 and 10, by the set-screw 69, so that it may be adjusted longitudinally thereon. As this sleeve 66 forms one of the conducting elements of the hereinbefore described secondary brake-setting circuit 75 through its uninsulated section, see Figs. 3, 8 and 10, it may be so adjusted on the said collar 68 that the rotation of the governor, which is operated by the pulleys 18 and 20 and belting 19, will slide the said uninsulated section thereof into contact with the conducting post 57 only when the speed of the train is greater than a given rate. If, however, such rate of speed is less than say, ten miles per hour, then, although a break 80 occur in the main engine circuit by reason of the contact of the third-rail element and shoe and the cab signal go to "danger," it is evident that the said secondary circuit will be incomplete as there will exist a break 85 therein at and because of the insulated section of the sleeve, due to the fact that the contact post 57 in said secondary circuit will then contact with the insulated section of the said sleeve, and that therefore the motor 90 32 will not be energized to operate the stopping mechanism.

It will be noted in Fig. 5 that the shoe members 24 are mounted on both sides of the engine and each may be brought separately 100 into the main engine circuit by means of the switch arrangement shown in Fig. 4 and which comprises a quadrant-lever 70 mounted upon the shaft 71 near the reversing apparatus of the locomotive, the wire 72 connecting with the battery 15, and the wire 25^a with the said shoe member on the right side of the engine and the wire 25^a with the shoe member on the left side of the engine, so that in case the engine is reversed to travel 105 in an opposite direction the proper shoe will be automatically brought into the main engine circuit and the corresponding shoe rendered inoperative. A recording device as described in Fig. 6 by the numeral 73 may 110 be employed to record the application of the brakes.

While I have particularly described the elements best adapted to perform the functions set forth, it is obvious that various 115 changes in the form, arrangements, proportions, and details of construction, may be resorted to, without departing from the spirit of the invention as set forth in the annexed claims.

Having described my invention, its advantages and operation, I claim as new and desire to secure by Letters Patent of the United States:—

1. In a train controlling device of the 130

- character described, a normally closed main engine circuit including a magnetic switch and a mechanically operated contact switch adapted to break said circuit, a normally open secondary engine circuit in said main circuit adapted to be closed by the armature of said magnetic switch upon opening of said contact switch, a motor in said secondary circuit energized upon closing of the 10 circuit as aforesaid, steam shut off mechanism and brake setting mechanism adapted to be operated by said motor, a governor operated speed controlling mechanism to close said secondary circuit when the train attains a predetermined speed, mechanism operated by said governor adapted to maintain said secondary circuit open subsequent to the opening of said mechanically operated contact switch, and a latch mechanism electrically interposed in said secondary circuit adapted to coöperate with the armature of said magnetic switch to complete and maintain said secondary circuit closed upon demagnetization of said magnetic switch.
2. In a train controlling device of the character described, a normally closed main engine circuit, a normally open secondary engine circuit adapted to be closed upon breaking of the main circuit, a motor in said 20 secondary circuit energized upon closing of the circuit as aforesaid, a source of current

for said secondary circuit, an auxiliary motor energized from the source of current of said secondary circuit, and an air release valve in the air brake line of the train actuated by 35 said auxiliary motor.

3. In a train controlling device of the character described, a normally closed main engine circuit and a normally open secondary engine circuit, a driven shaft having 40 its rate of rotation controlled by the speed of the train, a governor driven by said shaft, a pivoted indicator arm adapted to close said secondary circuit upon the train attaining a predetermined high rate of speed, a member 45 controlled by said governor and engaging said arm, a movable contact member in said secondary circuit carried by said governor, slidably movable therewith and having an insulated and a conducting section, and a 50 fixed contact in said secondary circuit adapted to engage the insulated portion of the movable contact member when the train is traveling at a predetermined low rate of speed to prevent closing of the secondary 55 circuit and to engage the conducting section of the movable contact member to allow closing of the secondary circuit when the train is traveling faster than at a given rate of speed.

In testimony whereof I affix my signature.
FRANK S. THAYER.
